TOWER PACKING FOR CHEMICAL DISTILLATION APPARATUS AND THE LIKE

Frederick W. Arndt, Bay Village, Ohio, assignor to Heil
Process Equipment Corp., Cleveland, Ohio

Filed Nov. 28, 1969, Ser. No. 20,304

Term of patent 14 years

Int. Cl. D24—02

U.S. Cl. D16—2

Fig. 1.

Fig. 2.

FIG. 1 is a perspective view of the tower packing, showing my new design;

FIG. 2 is a top plan view of a tower packing for chemical distillation apparatus and the like of FIG. 1;

FIG. 3 is a side elevation of the tower packing of FIGS. 1 and 2; and

FIG. 4 is a section of FIG. 3 on the line 4—4.

I claim:

The ornamental design for a tower packing for chemical distillation apparatus and the like, as shown.
